UNITED STATES PATENT OFFICE.

SAMUEL BERGSTEIN, OF MIDDLETOWN, OHIO, ASSIGNOR TO THE INTERSTATE FOLDING BOX COMPANY, OF MIDDLETOWN, OHIO.

PROCESS OF MAKING PAPER BOXES AND THE LIKE.

Application filed December 15, 1924. Serial No. 755,931.

This invention relates to a new process of making paper boxes, having particular reference to boxes in which certain portions thereof, as end or side portions, are glued together to effect the shape of the box and to give the same the strength required in its use.

The main object sought to be accomplished and attained in the practice of my invention is a new process, adapted to be practiced on any suitable apparatus, for making boxes variable shapes and sizes whereby box blanks cut and scored in the usual manner can be positioned on a forming device in such a manner that like parts thereof will be acted on by automatic mechanism to fold one part relative to another to apply an adhesive to the folded parts, and to apply pressure thereto whereby to effect joints of uniform adhesion, the necessary operations being performed in a progressive sequence in which all duplicate or similar operations on different parts of the box are made simultaneously.

A further object attained in the invention is a process of paper box making adapted to be practiced on a simple machine, having a relatively large output and adapted to be attended by an unskilled operator, thus making the practice of the invention available to users of paper boxes who wish to avoid carrying a large stock of ready made boxes, and at the same time to avoid the usual delays incident to the filling of small quantity orders by manufacturers.

The new process involves certain novel operations in connection with forming the adhesive joints which act to more firmly unite the coacting parts one with another and thus to produce joints of firmer adhesion and consequently of greater strength.

The new process may be practiced on any suitable apparatus, a preferred construction being shown in the accompanying drawings and described in detail in the following specification, for the purpose of illustrating the practice of the invention.

In the drawings:

Fig. 1 is a side elevation of the machine partly in section;

Fig. 2 is a detail elevation of the adhesive applying mechanism;

Fig. 3 is a side elevation of the machine taken at right angles of Fig. 1;

Fig. 4 is a side elevation of the gear train for operating the machine;

Fig. 5 is a detail sectional view of the box ejecting mechanism;

Fig. 6 is a plan view of the worktable;

Fig. 7 is a detail side elevation of the worktable and box supporting units;

Figs. 8 and 9 are detail views of the joint forming mechanism.

The apparatus here shown consists of co-ordinated mechanisms arranged on a vertical column 1, having a base 2 and a head 2^a, a work-head supported rotatably in a horizontal plane on column 1 and consisting of four radially extended arms 3 which are arranged at right angles one relative to the other,—each of the arms 3 being provided with a box forming block 4. Associated with the work-head and adapted to coact with the forming blocks 4 are a duplex gluing mechanism 5—6 and a duplex joint-forming 7—8 and coordinated mechanisms which will presently be described in the detailed specification. Operation of the several units of the machine is effected by means of a power head comprising a motor 9, reduction and transmission gearing 10, 11, 12, 13, 14 and 15 constituting a geared transmission from the motor 9 to the main drive shaft 16; a belt and balance wheel 17 being interposed between gears 11 and 12, the same being adapted to have a power belt applied thereto for operating the machine independently of the motor 9. Gear 15 is mounted free on drive shaft 16, its operative relation therewith being controlled by means of a spring tensioned clutch mechanism 18 which is in turn controlled by a trip pin 19 connected by a rod 20 to a treddle 21 in base 2 of the machine,—the clutch mechanism being of well known construction and commonly known as a tight-and-loose pulley connection.

Rotatable movement is transmitted from shaft 16 to the work-table through bevel gears 22—23, shaft 24, bevel gears 25, 26, shaft 27, pin gear 28, Geneva gear 29, spur gears 30, 32, 33 and bevel gears 34—35, the gear 35 being secured to the work-table. As here shown, the gearing is timed to cause a quarter-turn of the work-table upon each full rotation of the pin gear 28 which advances the Geneva gear 29 a quarter turn upon each driving engagement therewith,

the entire gear train being retained at rest between operations of the Geneva gear by the interlocking relation between gears 28-29 in the manner well known in Geneva 5 gears.

The box forming blocks 4 are mounted on the radial extensions 3, which may properly be termed the work-table anvils, to have limited vertical movement relative thereto, 10 each block being formed of two pieces—an inverted U-shaped inner member 4^a which is connected direct to the anvil by means of pins 36 set in the opposite sides of the anvil and extended outward into vertically ex- 15 tended slots 37 in the opposite side walls of part 4^a. The relation of the parts are such that member 4^a has limited vertical movement, compression springs 38 being interposed between the anvil and the intermediate 20 wall of part 4^a, there being a spring inwardly adjacent each corner thereof, to support the forming block normally in raised position relative to the anvil. The other parts of the forming block consist of the 25 integral parts 4 which are secured to part 4^a in any suitable manner as by screws. Parts 4 of variable sizes are adapted to be used interchangeably on parts 4^a thus to adapt the machine for making boxes of different 30 sizes.

The forming blocks are also provided with retaining clips 39 arranged adjacent both ends of the block on opposite sides thereof, which serve to hold the box blanks E in 35 position on the blocks during the gluing and joint forming operations. Each forming block is also provided with ejector, or kick-off mechanism for removing the finished box therefrom. This mechanism is composed of 40 a lever 40 pivoted as at 41 on each of parts 4^a and provided at its lower free end with a roller or cam follower 42 disposed in the horizontal plane of an outwardly extended cam 43 secured to column 1 of the machine, 45 the coaction between the parts resulting in a reciprocal movement being given to lever 40 upon each full rotation of the work-table. A link 44 is connected to lever 40, intermediate roller 42 and its pivot center, and to 50 a rocker arm 45 secured to a transversely extended shaft 46 supported to part 4^a. A downwardly extended kicker arm 47 is fastened to shaft 46 and is thus adapted to be reciprocated outwardly upon each actuation of lever 40. An upwardly extended kicker arm 48 is secured to a rocker shaft 49 supported in the lower walls of part 4 and is operatively connected with arm 47 by means of a roller 50 provided on arm 47 55 intermediately its ends. It will be observed that there are two of the arms 48 for each ejector mechanism and that arm 47 is interposed therebetween,—arms 47 and 48 being normally pressed inwardly and held in vertical relation relative to blocks 4 by a spring 60

51 coiled on shaft 49 which acts also to return the arms to normal position after each actuation thereof, the outward movement of the arms being effective to remove a box from the forming block, as will be more fully explained in the detailed description of the operation of the machine.

As best shown in the plan view of the work-table in Fig. 6, the forming blocks are moved successively into positions A, B, C 75 and D, the successive steps of forming a box beginning in position A where the attendant of the machine places the box blanks on the forming blocks. In the machine as here shown, this is done by hand, but it will be 80 clear to those skilled in the art to which the invention pertains that the box blanks can be readily positioned on the forming blocks by suitable automatic mechanism under conditions of use where it may be desirable for 85 one operator to attend more than one machine.

As shown in Fig. 6, the work-head has four work supporting units of identical construction which, when the machine is at rest, occupy positions A, B, C and D respectively, the direction of operation being counter-clockwise, as indicated by the arrow. In this position, opposite outwardly extended guides 52 are supplied to position the box for height on the box supporting block 4 so that the folds for forming the joints will be uniform on all the boxes. To this end, arms 52 are formed concave, V-shaped as here shown, on their under side to receive the open, upward extended flaps —a of the end of the box and to hold the same in vertical position until the first step of folding has been made. Arms 52 are supported on a bar 53 which is slotted as at 54 to allow varying the spacing of the arms relative to each other and to suit the width of the box for which the adjustment is made, bar 53 being in turn supported by a block 55 adjustable vertically on a rod 56 secured in a plate 57 fixed to the head support of the machine whereby to set the arms 52 according to the height of the end flaps —a of the box.

An arm 58 is pivoted on rod 56 at its base and in its idle position is drawn in clockwise direction against a stop 59 by a spring 60, the arm having secured therein a rearwardly extended, curved rod 61 which in turn has a finger 62 and curved rod 63 secured thereto, the rod 63 being adjustable on rod 61 longitudinally thereof. This mechanism serves to effect the first fold of the box,—a lug 64 extended upwardly from each end of the anvils 3 acting upon rotation of the work head to engage the finger 62 and thus to rock arm 58 on its pivot center and to move arm 63 forward, in advance of the movement of the work-head, into engagement with the adjacent end flap —a of the box at right angles over the edge of the forming block 130

4, spring 60 acting to retract arm 58 as lugs 64 pass out of engagement with finger 62.

The opposite end flap —a, upon rotation of the work head, is moved out of engagement with the other arm 52 and upon further advancement of the work head is brought into engagement with a circumferentially extended tubular rod 65 supported outwardly of the machine on brackets 66—67 in a plane and in a manner to effect a corresponding fold of the opposite flap —a, both flaps —a being then held in folded relation as the unit supporting the box moves to position B. Brackets 66—67 are slotted as at 68—69 and tubular rod is arranged telescopically with a second rod 70 to permit of adjusting the rods radially relative to the work head to suit variations in the size of boxes.

20 The outstanding improvement in the machine of the present invention over the machine of the former application for patent herein referred to, consists in the duplex arrangement of the work head mechanisms 25 which adapts the machine for forming both ends of the box simultaneously and thus to double the production capacity of the machine. To this end, duplicate mechanisms of parts 52 to 70 inclusive are arranged in 30 a lower plane of the machine and act on the opposite end of the box to effect folds thereon substantially in the same manner as in the first instance described, the duplicate parts being numbered 52^a and 70^a inclusive. The action on the opposite ends of the box is simultaneous, the arrangement and operation of the folding mechanisms in the upper and lower planes of operation being substantially the same except that the operations are in inverse order, i. e., the upper 35 end of the box is folded downward and the lower end is folded upward.

The adhesive for the joints is applied to the folded ends of the box in position B, the adhesive mechanism comprising upper and lower units coacting one with the other to apply the adhesive to both sides of the box simultaneously. The upper unit of the mechanism consists of an adhesive container 50 71 suspended on a bar 72 which is supported in open bearing slots 73 of spaced arms 74 formed integrally one with the other and mounted on the head casting of the machine to have vertical reciprocal action thereon, operable movement being given thereto by means of a pin and groove connection 75—76 with the main drive shaft 16; the details of the arrangement being of well known construction. The container 71 is provided 55 with a plurality of spring tensioned valve stops 77 coacting with ports in the bottom of the container, the ends of the valve stops extending through the ports and being adapted upon reciprocation of the container 60 to be brought into contact with the folded

upper ends of the box supported on the forming block. It will be understood that the valve stops act to close the ports when the container is in raised position, and on the down stroke of the mechanism when 70 their projecting ends come in contact with the end of the box on the forming block, and the same are pressed upward to open the ports and thus cause a regulated portion of adhesive to gravitate to the end of the stops, 75 the same act to affect a deposit of adhesive from each stop on the folded ends of the box blanks.

The lower unit of the adhesive applying mechanism consists of a container 78 supported on a plate 79, secured to column 1 by means of set screws 80 operable in slots 81 in plate 79,—the arrangement making provision for vertical adjustment of the container as required to suit the size of the 85 boxes. Acting with container 78 is an adhesive depositing mechanism comprising an angular-shaped member 82 secured to a vertically slidable member 83 by means of a set screw 84 operable in a slot 85 which 90 adapts part 82 to be adjusted vertically on part 83 in order to retain the same in normal relation with container 78. Part 83 is supported on part 79 by means of bearing blocks 86, and is adapted to be reciprocated 95 vertically by a pitman 87 connected to a pitman wheel secured to pin gear 28. The lower portion of member 82 extends over the adhesive container, which is open at the top, and has arranged thereon a series of 100 spring-tensioned pins 89 which are adapted to be submerged, upon the downward vertical reciprocation of part 82, in the liquid adhesive in container 78, and on the upward movement to be brought yieldingly in contact with the folded lower end of the box 105 on the supporting block 4 and thus to effect a deposit of adhesive thereon from each of the pins 89, the movement being timed to be substantially simultaneous with the deposit 110 of adhesive on the opposite end of the box from container 71.

As here shown, position C of the work table, is an idle position which allows a short pause in the sequence of operations to permit 115 the adhesive, applied to the parts of the box to be joined together, to cool and set to a desired extent before the joints are formed.

As the box supporting units move to position D, the coacting part —b of the ends 120 of the box is engaged by extended arms 90 and 90^a respectively of the mechanisms in the upper and lower planes of operation, and are folded over the previously folded parts —a as the unit is moved to position D 125 where the joints are formed under opposite pressure heads 7 and 8.

Pressure head 7 is reciprocally operable on the power head casting 2^a, being connected to main drive shaft 16 as at 75^a in a man- 130

ner similar to the connection 75 for actuating the adhesive container 71. The lower pressure head 8 is supported on a screw 91 adjustable vertically in a bearing extended outward from column 1. Coacting with screw 91 on opposite sides of bearing 92 are hand adjusting wheels 93 and 94 by means of which the screw and with it pressure head 8 can be raised and lowered and retained in adjusted position. By this arrangement the space between pressure heads 7 and 8 can be accurately regulated according to the height of the forming blocks 4, or the length of the boxes for which the machine is set up. From the illustrations of the drawings it will be understood that the upper end of the forming blocks is always in the same horizontal plane regardless of the height of the blocks, the variations of length being only in the lower plane of operation where provision is made for the same in the means for adjusting the lower adhesive and pressure mechanisms.

For any given length of box, the maximum distance between pressure heads 7 and 8 will be the length of the box, plus the extent of vertical movement of the forming blocks 4, the minimum distance being the length of the box with the ends compressed between heads 7 and 8 and the opposite ends of the forming block. It will thus be seen that the first action of pressure head 7 on the forming block will be to force the block downward against the resistance of springs 38 to the limit of the vertical movement of the blocks when the folded end portions of the box having the adhesive thereon will be firmly pressed together to form the joints, the amount of pressure applied in the operation being determined by the adjustment of screw 91.

As the forming blocks, carrying the completed boxes thereon, move from position D to position A, the cam follower 42 is brought into engagement with cam 43 and the ejector arms 47-48 are actuated to kick the box off the forming block which will then be ready to receive another box blank as it comes to a stop in the A position.

It will be noticed that the box supporting units 4 move in a plane and through a cycle of operation common to all the units, there being five successive steps of operation in the cycle, i. e., placing the box blanks on the forming blocks, folding the parts to be glued to form the joints, applying the adhesive to the folded parts, forming the joints under pressure and removing the finished product from the forming blocks upon completion of the cycle.

From the foregoing detailed description of an apparatus suitable for the practice

of my invention thereon, and of the invention as practiced on said apparatus, the sequence of operations comprised therein and the results accomplished, it will be seen that the invention provides a simple process for making boxes in large or small quantities at relatively low cost, that all duplicate or similar operations of folding, gluing and forming the boxes are made simultaneously, that a high degree of uniformity and general quality of construction is thus obtained.

As far as I am aware, the new process of box making as herein described and illustrated is broadly new in the art to which the invention pertains, the same being a radical departure from the present known practice of making paper boxes by automatic or semi-automatic machinery. The appended claims, therefore, define the invention as broadly new in the various combinations of its underlying principles, and also with respect to coordinated details of operation which adapt these principles to commercial practice under varied conditions of use.

Having described my invention, I claim:

1. The herein described process of making paper boxes, consisting in causing box blanks to be folded over forms with flaps extended and to be further subjected to successive mechanical operations; first, to effect simultaneous foldings of opposite like portions of said blanks; second, to cause a deposit of adhesive to be made on said opposite folded portions; third, to cause other like portions of the blanks to be folded over the first folded portions; and fourth, to effect adhesion between the folded portions.

2. The herein described process of making paper boxes consisting in causing box blanks to be folded over forms with flaps at opposite ends extended, and moved step by step with operating pauses between steps through a sequence of simultaneous folding, gluing of folded portions, and joint forming operations at opposite ends of the box whereby to effect the structure thereof, the respective operations resulting simultaneously on different boxes.

3. The herein described process of making paper boxes consisting in positioning box blanks on forms acting to determine one or more dimensions of a box, in causing the blanks so supported to be rotated with flaps extended in opposite planes parallel to the plane of the axis of rotation, in simultaneously effecting folds of said oppositely extended portions, in applying adhesive to said folded portions, and in compressing the folds to effect adhesion therebetween.

In testimony whereof, I affix my signature.

SAMUEL BERGSTEIN.
